BRUSH

Samuel J. Langer, Troy, N. Y., assignor to Tek
Hughes, Inc., a corporation of New York

Application April 10, 1948, Serial No. 145,632

Term of patent 14 years

(Cl. D86—10)

To all whom it may concern:

Be it known that I, Samuel J. Langer, a citizen of the United States, residing at Troy, in the county of Rensselaer and State of New York, have invented a new, original, and ornamental Design for a Brush, of which the following is a specification, reference being had to the accompanying drawing, forming a part thereof, in which

Fig. 1 is a bottom plan view of a brush showing my new design;

Fig. 2 is a side view of the brush;

Fig. 3 is a top plan view of the brush;

Fig. 4 is an end elevation taken from the top of the drawing in Fig. 3;

Fig. 5 is a section on the line 5—5 of Fig. 3; and
Fig. 6 is a section on the line 6—6 of Fig. 3.

I claim:

The ornamental design for a brush, as shown.

SAMUEL J. LANGER.
